OF NO 19,150

DESIGN.

E. L. CALEY.
PORTABLE FIRE PLACE GRATE.

No. 19,150.

Patented June 11, 1889.

UNITED STATES PATENT OFFICE.

EDWARD L. CALEY, OF PHILADELPHIA, PENNSYLVANIA, ASSIGNOR TO GILBERT COMBS, JOHN BAWDEN, AND JOHN H. BAWDEN, OF FREEHOLD, NEW JERSEY.

DESIGN FOR A PORTABLE FIRE-PLACE GRATE.

SPECIFICATION forming part of Design No. 19,150, dated June 11, 1889.

Application filed January 9, 1889. Serial No. 295,882. Term of patent 7 years.

To all whom it may concern:

Be it known that I, EDWARD L. CALEY, a citizen of the United States, and a resident of Philadelphia, Pennsylvania, have invented 5 a new and original Design for a Portable Fire-Place Grate, of which the following is a specification.

My design for a fire-place grate is fully shown in the accompanying photographic 10 illustration.

The contour of the upper edge of the back and jambs is scroll-like. On the center of the back is a panel with a border of three prominent lines, the central line being made 15 up of a series of dashes. The corners of the borders are ornamented with rosettes, and running diagonally across the body of the panel are two lines, between which is a foliated design, and on each of the remaining triangular sections are also foliated designs. 20 Above the panel is a central ornament with rosettes at each end.

The design of the front plate of the grate consists of a series of scroll open-work with 25 a bar running through the centers of the

scrolls. On the upper edge of the front plate is a scroll supported by a series of vertical posts.

The design of the side plates is of the same general character as and in keeping with that 30 of the back plate.

I claim—

1. The design for the back plate of a fire-place grate, said design consisting of a quadrangular panel ornamented with foliated and 35 diagonal lines, substantially as described, and shown in the accompanying photographic illustration.

2. The design for a fire-place grate, substantially as described, and as shown in and 40 by the accompanying photographic illustration.

In testimony whereof I have signed my name to this specification in the presence of two subscribing witnesses.

EDWARD L. CALEY.
